UNITED STATES PATENT OFFICE.

HENRY A. EVERETT, OF HADDON HEIGHTS, NEW JERSEY.

OVERLOAD CIRCUIT-BREAKER.

1,182,900.

Specification of Letters Patent.

Patented May 16, 1916.

Application filed February 24, 1915. Serial No. 10,203.

To all whom it may concern:

Be it known that I, HENRY A. EVERETT, a citizen of the United States of America, residing in Haddon Heights, in the county of 5 Camden and State of New Jersey, have invented a certain new and useful Improvement in Overload Circuit-Breakers, of which the following is a true and exact description, reference being had to the accompanying drawings, which form a part thereof.

My present invention consists in an improved form of overload circuit breaker adapted to be connected in circuit with an electric motor to interrupt the current flow 15 therethrough on a predetermined rise and duration of that current flow.

The object of my invention is the provision of an overload circuit breaker of simple construction which is automatic and reliable 20 in operation, is readily portable and adapted to operate in any position in which it may be placed, and is not apt to be injured, or to have its operativeness interfered with by rough usage.

My invention was primarily devised for 25 use in connection with portable electric drills and reamers of the kinds used in ship yards, bridge work and elsewhere, where heavy drilling and reaming operations are carried out under like conditions. For such 30 use it has now become desirable to employ quite powerful electric driven portable drills and reamers. In consequence when a drill or reamer bit sticks, as it frequently does 35 when crowded into the work, the powerful motor is apt to twist the bit off, and if the bit is not broken in this manner, it frequently happens that the motor tears loose from the grasp of the operator, and this, of 40 course, is apt to result in injury to the workman, as well as damage to the tool. If the bit sticks and the motor frame is firmly held by the operator, the motor is apt to "burn out" because of the failure of the workman 45 to open the motor switch quickly enough, especially as these tools are ordinarily operated by unskilled workmen. While there is thus more need for a suitable overload circuit breaker for the protection of an electric 50 motor, used as above specified, than in the ordinary uses of such motors, the conditions of the use referred to which make the circuit breaker especially desirable, make the ordinary types of overload circuit breakers 55 heretofore devised unsatisfactory, because they do not possess the needed ruggedness

and ready portability coupled with reliability of operation.

The various features of novelty which characterize my invention are pointed out with particularity in the claims annexed to and forming a part of this specification. For a better understanding of the invention, however, and of the advantages possessed by it, reference should be had to the accompanying drawings and descriptive matter, in which I have illustrated one form of my invention.

Of the drawings: Figure 1 is a view which may be regarded either as a plan or an elevation of my novel safety device, with its cover removed; Fig. 2 is a section taken on the line 2--2 of Fig. 1; Fig. 3 is a section taken on the line 3--3 of Fig. 1; and Fig. 4 is a diagrammatic representation of the circuit connections employed.

In the form disclosed in the drawing, my improved safety device comprises a board or block of insulating material A, forming a support on which the rest of the mechanism is mounted. This mechanism comprises a switch mechanism including a stationary contact B, the base B' of which is secured to the support A, and a coöperating contact C, carried by a bell crank or switch lever C'. The latter is pivoted between the ears D' of a bracket D, secured to the support A. To the upper end of the upper arm of the bell crank C' is secured a transverse pin C². The ends of the pin C² are connected by helical springs F, to the ends of a pin E which is parallel to the pin C², and to the axis of the switch lever C', and works in slots D², formed in the bracket ears D'. The slots D² extend generally parallel to the plane of the support A and as the pin E is moved from one set of ends to the other of the slots D², the lines of action of the springs F shift from one side to the other of the fulcrum of the switch lever C' and the switch accordingly opens or closes with a snap. Links G connect the ends of the pin E to the end of the hollow magnetic armature core H' of an electric magnet H of the solenoid type mounted on the support A with its axis generally parallel to the direction of the slots D². As shown, the frame or spool of the electromagnet H is formed at the end remote from the switch mechanism with a dash-pot cylinder H², in which works a dash-pot piston J, connected to the inner end of the armature core H' by the non-

magnetic rod J' , and the pin J^2 . The winding of the electromagnet H comprises a shunt coil i and a series coil I . The armature H' is constantly urged into the position in which it extends out of the electromagnet and the switch contact C is held against the contact B by resilient loading means, which in the form shown, comprise a pair of helical springs K located on opposite sides of the electromagnet and each connected at one end to a corresponding lug J^2 on the dash-pot piston J . At its opposite ends, each spring K is connected to a corresponding bolt L , passing loosely through an aperture in an ear H^3 formed on the end flange of the spool of magnet H adjacent the switch mechanism. By adjusting the nuts L' on the bolts L the tension of the springs K may be varied to meet different operating conditions.

Advantageously a magnetic blow-out coil M is mounted on the support A in position to minimize sparking when the switch contacts B and C are separated. Advantageously, the electromagnet and switch mechanism are inclosed by a box like case of sheet metal N , fitting over the edges of the support A and secured to the latter by means of the screws N' .

As shown, the two insulation covered supply conductors O and OA , which are inclosed in a single insulating jacket external to the safety device, are secured to one end of the support A by binding posts or clamping screws P and P^3 respectively. To the opposite end of the support A binding posts P' and P^2 secure the ends of insulation covered conductors O^4 and OA^2 leading to the motor R to be protected. External of the safety device the conductors O^4 and OA^2 are inclosed in a common insulating jacket. As illustrated in Fig. 4, the binding post P to which the supply conductor O is secured, is also connected to one terminal of the blow-out coil M . The other terminal of the latter is connected to the base B' of the stationary switch contact B . The bracket D , and thereby the switch lever C' , and contact C , are connected by a conductor O' , to one terminal I' of the series winding I of the electromagnet, and a branch O^2 of the conductor O' is connected to one terminal i' of the shunt winding i . A conductor O^5 connects the binding post P' to the second terminal i^2 of the shunt winding i . As seen in Fig. 4, several taps I^2 , lead from different portions of the winding I , and the conductor O^3 serves to connect one or another of these taps I^2 to the binding post P' . In the conductor O^4 , leading from the binding post P^3 to the motor R is connected the operating switch Q for the motor R . Conductor OA' extends between the binding posts P^2 and P^3 and thereby connects conductors OA and OA^2 .

In operation, with the normal current flow in series through the coil I and motor R , the tension of the springs K prevent movement of the armature H' sufficient to separate contacts B and C , for while, with what may be regarded as normal current variations, the armature H^3 moves back and forth slightly as the current varies, these movements do not result in separating the contacts. It is only when the movements of the armature is sufficient to carry the axis of the pin E to the right, as seen in Fig. 2, of the plane including the axis of the pins C^2 and the axis of the switch lever C' , that the contact C is moved out of engagement with the contact B . When the movement of the armature is sufficient to separate the contacts, however, the contacts separate with a rapid or snap action. When the contacts thus separate and the main circuit is thus broken, the coil I is thereby deenergized and thus does not oppose an immediate return of the apparatus to its normal condition in which the contacts B and C are in engagement. This immediate return is prevented, however, by the shunt coil i which is energized with practically the full potential of the supply circuit as soon as current flow between the contacts B and C is interrupted. To deenergize the winding i and thus permit the return of the apparatus to the condition in which contact C engages the contact B , it is necessary to open the circuit external of the safety device proper. In practice the workman handling the tool of which the motor R is the driving agent, opens the switch Q to deenergize the coil i . This requirement for some active operation on the part of the workman before restarting his motor after the operation of the safety device, is desirable, as it brings to his immediate attention the fact that the tool should be backed off or adjusted to reduce the resistance of the work to its movement. The dash-pot is an essential characteristic of my device when used with the electric drills and reamers for which it was especially devised, because with these tools there is a momentary current flow when the operating switch (Q) is closed, necessary to start the motor, which is substantially in excess of the working current which can be safely passed through the motor for any appreciable length of time. The dash-pot operates to prevent the opening of the motor circuit on this momentary rush of a current appreciably greater than the current which, if continued for a few seconds would, and should result in the operation of the circuit breaker.

The strength of the maximum working current which the safety device will permit to pass may be varied by changing the tap I^2 connected by the conductor O^3 to the binding post P' and thereby in effect short-

ening or lengthening the winding I, and may be adjusted also by changing the tension of the springs K.

In the practical use of the electric drilling and reaming tools with which my invention is employed, the tools, ordinarily, are not continuously, or for any considerable length of time, connected at the same point to fixed supply conductors, but are plugged into and out of circuit with the fixed conductors at different points at comparatively frequent intervals as the tools are shifted. The same permanent supply conductors to which any one tool may thus be connected at numerous different points supplies current, in ordinary practice, to numerous tools and lights. In consequence, it is essential that the safety device be portable with the motor which it is employed to protect. In practise the portions of the motor supply conductors extending between the motor and the safety device are a few feet in length to permit the safety device to be hung up on a wall or dropped on a ship's deck, bridge girder or other convenient place of support in proximity to the point at which the tool is used.

It will be apparent to those skilled in the art that my improved safety device while compact, simple in construction and relatively light in weight, is rugged and reliable in operation, and operative in any position which it may be placed. Ordinarily I attach a chain O, as shown, to the support A to permit the device to be hung up at any convenient place in proximity to the tool with which it is employed, but the device will operate equally well when lying flat or inclined.

While in accordance with the provisions of the statutes I have illustrated and described the best form of my invention now known to me, it will be obvious to those skilled in the art that changes may be made in the form of apparatus disclosed without departing from the spirit of my invention.

Having now described my invention, what I claim as new and desire to secure by Letters Patent, is—

1. In an overload circuit breaker the combination of a switch including a movable switch opening and closing member, a movable armature, a mechanical connection between said armature and member including provisions for some lost motion and arranged to permit a limited initial movement of the armature in the switch opening direction without moving said member, but operating on a further movement of the armature to force said member into the switch open position, yielding means tending to return the armature to and maintain it in the position in which the switch is closed, a winding in series with said switch adapted on a predetermined flow of current there-

through to move the armature into the switch open position, a winding in shunt to the switch and tending when energized to hold the armature in the switch open position.

2. In an overload circuit breaker the combination of a switch including a movable switch opening and closing member, a movable armature, a mechanical connection between said armature and member including provisions for some lost motion and arranged to permit a limited initial movement of the armature in the switch opening direction without moving said member but operating on a further movement of the armature to force said member into the switch open position, yielding means tending to return the armature to and maintain it in the position in which the switch is closed, a winding in series with said switch adapted on a predetermined flow of current therethrough to move the armature into the switch open position, a winding in shunt to the switch and tending when energized to hold the armature in the switch open position, and a dash pot opposing a rapid initial movement but yielding to permit a rapid final movement of said armature in the switch opening direction.

3. In an overload circuit breaker the combination of a quick acting switch mechanism comprising a movable contact, a reciprocating element and a resilient connection between said element and contact put under tension during and snapping said contact into open position at the end of a predetermined movement in one direction of said element, a dash-pot retarding the initial but not the final portion of said predetermined movement of said element and an electromagnet including a winding adapted to be connected in series with said contact in the circuit to be controlled and an armature attached to and actuating said element.

4. In an overload circuit breaker, the combination of a quick acting switch mechanism comprising a movable contact, a reciprocating element and a resilient connection between said element and contact put under tension during and snapping said contact into open position at the end of a predetermined movement in one direction of said element, an electromagnet comprising an armature connected to said element and effecting the predetermined movement thereof when sufficiently energized, and a winding, said winding and contact being adapted to be connected in series in the circuit to be controlled, and the frame of said electromagnet being formed with an open ended chamber at one end, and a piston connected to said armature and working in said piston chamber and forming with the latter a dash-pot to retard the armature during the initial portion of, but not the final por-

tion of said predetermined movement of said element.

5. A portable overload circuit breaker comprising in combination, a support, a stationary contact mounted thereon, a bracket mounted thereon, a bell crank switch lever C' pivoted in said bracket and carrying a contact normally engaging said stationary contact, said bracket being formed with 10 guides, an element E adapted to reciprocate in said guides, a resilient connection between said lever C' and said element E, the line of action of said connection being shifted from one side to the other of the pivotal 15 axis of the lever C' as said element is reciprocated in said guides, an electromagnet comprising a frame mounted on said support, an armature connected to, and tending to move said element in said guides, and 20 a winding, said winding and contacts being adapted to be connected in series in the circuit to be controlled, the frame of said electromagnet being formed with a piston chamber, and a piston connected to said armature 25 and working in said chamber and coöperating with the latter to form a dash-pot retarding the initial but not the final portion of the movement of the armature necessary 30 to shift the movable contact from its normal into its open position, and means for imposing an adjustable loading force on said armature tending to maintain the latter in the position in which said movable switch contact is held in its closed position.

35 6. A portable overload circuit breaker

comprising in combination, a support, a stationary contact mounted thereon, a bracket mounted thereon, a bell crank switch lever C' pivoted in said bracket and carrying a contact normally engaging said stationary 40 contact, said bracket being formed with guides, an element E adapted to reciprocate in said guides, a resilient connection between said lever C' and said element E, the line of action of said connection being shifted from 45 one side to the other of the pivotal axis of the lever C' as said element is reciprocated, an electromagnet comprising a frame mounted on said support, an armature connected to, and tending to move said element in said guides, and a winding, said winding and contacts being adapted to be connected in series in the circuit to be controlled, the frame of said electromagnet being formed with a piston chamber, a piston connected 50 to said armature and working in said chamber and coöperating with the latter to form a dash-pot retarding the initial but not the final portion of the movement of the armature necessary to shift the movable contact from its normal into its open position, and means for imposing an adjustable loading force on said armature tending to maintain the latter in the position in which said movable switch contact is held in its closed position.
